Primary Examiner — Katrina A Betton*(74) Attorney, Agent, or Firm* — The Dobrusin Law Firm, P.C.(57) **CLAIM**

The ornamental design for a hood latch, as shown and described.

DESCRIPTION

FIG. 1 is a perspective view of a hood latch showing our new design;

FIG. 2 is a top view thereof;

FIG. 3 is a bottom view thereof;

FIG. 4 is a side view thereof;

FIG. 5 is another side view thereof;

FIG. 6 is a front view thereof; and,

FIG. 7 is a back view thereof.

In the drawings, broken lines depict portions of the hood latch that form no part of the claimed design.
